Michael Bartholomew(57) **CLAIM**

The ornamental design for a diatomaceous sprayer as shown and described.

DESCRIPTION

FIG. 1 is a front, left and top perspective view of a diatomaceous sprayer, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the diatomaceous sprayer that form no part of the claimed design.

The area inside the dashed broken lines also forms no part of the claimed design.
